UNITED STATES PATENT OFFICE.

WILLIAM B. MEEKER, OF DAYTON, OHIO, ASSIGNOR TO THE AUTOMATIC LAMP CONTROL COMPANY, OF DAYTON, OHIO, A CORPORATION OF OHIO.

LAMP.

1,164,738.

Specification of Letters Patent. Patented Dec. 21, 1915.

Application filed April 28, 1913. Serial No. 764,072.

To all whom it may concern:

Be it known that I, WILLIAM B. MEEKER, citizen of the United States, residing at Dayton, in the county of Montgomery and 5 State of Ohio, have invented certain new and useful Improvements in Lamps, of which the following is a specification.

My invention relates to vehicle lamps and particularly to dirigible lamps in which the 10 direction of the shaft of light of the lamp may be varied with each deviation of the vehicle from a straight path.

The invention is applicable to vehicles of any type such as horse drawn wagons or 15 carriages, traction cars, locomotives, boats, vessels or bicycles, but is particularly adapted for use upon automobiles.

The object of the invention is to simplify the structure as well as the means and mode 20 of operation of such devices, whereby they will not only be cheapened in construction, but will be more efficient in use, positive and automatic in their action and unlikely to get out of repair.

25 A further object of the invention is to provide means for varying the direction of the shaft of light without varying the relative position of the lamp itself in relation with the vehicle.

30 With the above primary and other incidental objects in view as will more fully appear in the specification, the invention consists of the features of construction, the parts and combinations thereof and the 35 mode of operation or their equivalents, as hereinafter described and set forth in the claims.

Referring to the drawings, Figure 1 is a 40 plan view of the forward portion of an automobile to which a pair of lamps, forming the subject matter hereof, together with their controlling devices have been applied.

Fig. 2 is a front elevation of one of the 45 lamps. Fig. 3 is a vertical sectional view of the lamp and control device. Fig. 4 is a 50 sectional plan view of the lamp. Figs. 5 and 6 are a vertical sectional view and a sectional plan view respectively of a modification of the construction shown in Figs. 3 and 4. Figs. 7 and 8 are corresponding views of 55 a further modification. Fig. 9 is a sectional

plan view of a lamp having three positions of operative adjustment.

Like parts are indicated by similar characters of reference throughout the several 55 views.

The lamp forming the subject matter hereof differs from dirigible lamps as usually constructed. The lamp as herein described is secured in fixed position in relation with 60 the vehicle upon which it is carried and is not variable from such fixed position as is usual in dirigible lamp construction.

The lamp herein described is provided with two or more angularly arranged faces 65 or light openings, through any one of which the shaft of light may be directed by a variable controlling element mounted within the lamp. This controlling element may be either a movable reflector or a blind or shutter, controlled in unison with the deviation of the vehicle from a straight path by any of the controlling mechanism commonly employed for varying adjustable lamps in unison with the movement of the vehicles. It 70 is obvious that the control mechanism may be employed to adjust the variable element of either lamp independent of the vehicle in a corresponding direction or the element of both lamps may be adjusted in unison. 75

In the drawings there has been shown a simple and efficient method of independently adjusting the variable elements of the lamps according to the direction of the deviation of the vehicle from its straight path. The 80 controlling mechanism disclosed in the drawings is similar to that shown and described in my copending application, Serial No. 714,657, and forms no part of the present invention. It is obvious, however, that 85 any other suitable controlling mechanism may be employed in lieu of that herein shown.

Referring to the drawings, 1 is a forward portion or hood of an automobile of which 90 2 is the front axle. The forward wheels 3 of the vehicle are connected with the axle 2 by the usual swivel connections. The guiding wheels 3 are turned upon their swivel connections by the reciprocatory movement 100 of the steering bar 4, operated from a suitable steering wheel or control lever, not

shown in the drawings. The steering bar 4 is connected to an arm 5, carried by the swivel connection of one of the guiding wheels. Each of the swivel connections carries an arm 7, connected by a transverse rod 6, whereby the wheels are caused to move in unison. This is the ordinary automobile construction.

Carried upon forward extensions of the 10 frame bars 8 of the vehicle, are brackets 9, each terminating in a horizontally disposed disk 10. Journaled in the disk 10 is a vertical shaft 11, to which is secured a second disk 12. The disk 12 rests upon the disk 10 15 and forms a thrust bearing for the shaft 11. The disks 10 and 12 are recessed and in said recess is located a helical retracting spring 13, adapted to return the shaft 11 and disk 12 to their normal position when oscillated therefrom. A pin or stop 14, carried by the disk 12, engages a corresponding stop, carried by the stationary disk 10 to limit such return movement of the shaft and disk 12 under the influence of the spring 20 25 13. At its lower extremity the shaft 11 carries an additional disk 15 also secured thereto and moving in unison with the shaft. Loosely journaled upon the shaft 11 intermediate the stationary disk 10 and the disk 30 35 15 carried by the shaft, is a disk 16 provided with two radially disposed arms 17 and 18. The disk 16 carries a stop 19 adapted to engage with a corresponding stop carried by the disk 15.

35 The construction is such that when the disk 16 is rotated upon the shaft 11 in one direction, its stop 19 will engage the corresponding stop of the disk 15 and will rotate the disk 15 and the shaft 11 with 40 which it is connected in unison with the movement of the disk 16 against the tension of the retracting spring 13. When the free disk 15 is oscillated in the opposite direction it will move independent of the disk 45 15 and the shaft 11 and the latter will not be affected thereby. The disk 16 and the disk 15 at the opposite sides of the vehicle are oppositely connected, that is their interengaging stops are oppositely arranged so that 50 when the disks 16 are oscillated in one direction the stop 19 of one of said disks will engage the stop of the corresponding disk 15, while the other disk 16 will rotate free and when oscillated in the opposite direction the 55 opposite disks 15 and 16 will be interengaged. In order that the disks 16 may be oscillated in unison, the radial arms 17 of said disks at opposite sides of the machine are connected by a transverse connecting 60 rod 20.

To oscillate the disks 16 with each deviation of the vehicle from a straight path, and thereby oscillate the vertical shaft 11 corresponding to the direction in which the vehicle is turned, there is provided an actuat-

ing bar 21 extending parallel with the steering bar 4 and connected at its forward end to the radial arm 18 of one of the free disks 16. The steering bar 4 carries a laterally extending arm 22, having a perforated head 70 23 through which the actuating bar 31 projects. Located about the actuating bar 21 on each side of the head 23 is a helical compensating spring 24. The reciprocatory movement of the steering bar 4, necessary 75 to turn the vehicle from its straight path will be transmitted through the arm 22 and the springs 24 to the actuating bar 21, causing a corresponding reciprocatory movement of the actuating bar. This movement 80 of the bar 21 will cause a corresponding oscillatory movement of the disks 16.

If the vehicle is being turned to the right, the actuating bar 21 will be reciprocated in a forward direction, thereby oscillating the 85 disks 16 in one direction. If the vehicle is turned to the left the reciprocatory movement of the actuating bar 21 will be rearward, turning the disk 16 in an opposite direction. The direction of rotation of the 90 disks will depend upon whether the arm 18 extends inward or outward from the disk. In the construction shown in Figs. 5 to 8 the disk should oscillate in a direction corresponding with the direction of movement 95 of the vehicle from a straight path. In the construction shown in Figs. 3 and 4 the disks are oscillated in a direction opposite to the movement of the vehicle.

As before stated the disks 16 are connected 100 with the disks 15 in opposite relation, whereby only one of the shafts 11 will be oscillated with the movement of the disks 16 in either direction. The initial movement of the actuating bar 21, serves to rotate the 105 disks 16 and the corresponding shaft 11 moved thereby to the limit of their stroke, while any further movement of the guiding wheels 3 and the steering bar 4 is compensated for by the compression of the 110 spring 24.

The construction thus far described is identical with the construction set forth in the aforementioned copending application, and forms no part of the present invention, 115 but is claimed in said separate application. It has been herein set forth in detail that the independent operation of the light controlling element hereinafter mentioned may be more fully understood. It is to be understood, however, that the particular mechanism before described is not essential to the successful operation of the lamp herein-after described, but that other control mechanism may be substituted therefor.

The lamp forming the subject matter hereof comprises a housing or chamber 25, having two or more angularly arranged illuminating faces or openings 26 and 27. These illuminating faces or openings are 130

preferably provided with the usual transparent closures of glass or other material. Located within the chamber or housing 25 at a point common to both the illuminating faces or openings 26 and 27 is a burner, electric bulb or any other illuminating device 28.

The lamp is secured immovably upon the vehicle by any suitable means. The usual supporting fork may be employed but in the drawing the lamp has been shown as attached to an upward projecting arm 29, carried by the bracket 9 and further supported by a lateral arm 30, extending from the upward arm 29 and carrying a hub or sleeve 31, through which the revoluble shaft 11 projects.

When securing the lamps to the vehicle, they are arranged in such relation therewith, that the illuminating face 26 of each lamp will be directed forward in a line coincident with the path of travel, while the adjacent illuminating faces 27 will be directed outward at an inclination to the line of travel, one of such faces being directed to the right and the other to the left, as shown in Fig. 1.

To control the shaft of light from the illuminating device 28, whereby it may be directed at will through either of the illuminating faces 26 or 27, various means may be employed such as a variable shutter adapted to close one or the other of the illuminating faces 26 or 27, as shown in Figs. 3 and 4, or a reflector may be used to direct the shaft of light only through the selected illuminating face or opening as shown in Figs. 5 and 6 or a combination of the variable shutter and variable reflector may be employed, as shown in Figs. 7 and 8.

Referring to Figs. 3 and 4, there is secured in fixed position with the housing 25, a reflector 32 arranged in such relation with the burner or illuminating device 28 that it will direct the rays of light from such burner or illuminating device simultaneously through both the illuminating faces or openings 26 and 27. Carried upon the upper extremity of the shaft 11 and within the housing or chamber 25 is a radial arm 33 upon which is carried a vertical blind or shutter 34 adapted to be moved alternately into registry with the illuminating faces or openings 26 and 27, by the oscillation of the shaft 11. Thus when the blind

is in registry with the illuminating face or opening 27, as shown in Fig. 4, the light will be directed only through the illuminating face 26 and therefore in line with the straight path of travel of the vehicle. However, if the vehicle should be turned to the left, the blind 34 as shown in Fig. 4 would be oscillated to the position shown by dotted lines, where it would close the illuminating face or opening 26 and the rays of light 35 would be directed at an inclination to the

straight path of travel of the vehicle, in the direction to which the vehicle was being turned. Thus the lamp itself comprising the housing or chamber 25, the illuminating faces 26 and 27, the burner or illuminating device 28 and the reflector 32 remain stationary or fixed in their relation with the vehicle, while only the blind 34 moves in unison with the deviation of the vehicle from a straight path, causing the direction 70 of the shaft device to be varied in unison with the deviations of the vehicle.

Referring to Figs. 5 and 6 the construction of the lamp and its relation with the vehicle is identical with that before described. However in this construction, in lieu of the variable blind or shutter 34, a reflector 35 is carried upon the upper end of the shaft 11 and is operated in unison therewith, with each oscillatory movement 85 of the shaft. It is to be understood that the reflector 35 moves in a path concentric with the burner or illuminating device 28. In Fig. 6 the reflector 35 has been shown in a position adapted to direct the rays of light 90 straight forward through the illuminating face 26. When in this position the reflector concentrates the rays of light through the illuminating face 26 and but little light is permitted to pass through the angularly disposed face 27. However upon a deviation of the vehicle to the left, which as before mentioned will cause an oscillatory movement of the shaft 11, the reflector 35 will be oscillated about the burner or illuminating device 28, to a position shown by dotted lines in Fig. 6, in which position the shaft of light will be directed through the illuminating face 27 to the exclusion of the face 26.

While the most intense shaft of light will be directed by the reflector 35 through the illuminating face or opening with which the reflector is in registry, it is obvious that there will be some diffusion of light through the angular illuminating face or opening. Under ordinary circumstances such diffusion of light through the angular face is not objectionable. However to overcome this diffusion of light laterally at the time that the main shaft is directed forward, there is provided as shown in Figs. 7 and 8 a construction embodying both the variable blind and the variable reflector, operating in unison.

Referring to Figs. 7 and 8, the construction of the lamp and the relation of its several parts one with the other, and with the vehicle is the same as before described. The reflector 36 of this construction corresponds with the reflector 35 of the construction shown in Figs. 5 and 6. This reflector 36 is mounted at the rear end of a sleeve 37 which is carried upon the upper extremity of the shaft 11. The sleeve 37 is of such length that its forward or open end may be 130

brought into registry with either the illuminating face 26 or the face 27 by the oscillatory movement of the shaft 11. Immediately above the shaft 11, the sleeve 37 is provided 5 with an opening 38, through which the burner or illuminating device 28 projects.

In Fig. 8 the sleeve 37 and the reflector 36 are shown in a position adapted to direct 10 the shaft of light through the illuminating face or opening 26 and in line with the straight path of travel of the vehicle. However upon the oscillatory movement of the shaft 11 due to the deviation of the vehicle from such straight path the sleeve 37 and 15 the reflector 36 are oscillated through a path concentric with the burner or illuminating device 28 to the position indicated by dotted lines in said Fig. 8, whereupon the shaft of light will be directed through the angular 20 face 27 to the exclusion of the face 26. In this construction the sleeve 37 serves as a blind or shutter to exclude the unregistered face or opening and to concentrate the shaft of light through the face or opening with 25 which the reflector 36 is in registry.

In Fig. 9 is shown a construction embodying a multiplicity of illuminating faces, through any of which the shaft of light may be directed by the adjustment of the reflector 30 36 as before described. It is to be understood that the reflector has different positions of adjustment corresponding to the different faces.

From the above description it will be apparent 35 that there is thus provided a device of the character described, possessing the particular features of advantage before enumerated as desirable, but which obviously is susceptible of modification in its form, proportion, detail construction or arrangement of parts, without departing from the principle involved or sacrificing any of its advantages.

While in order to comply with the statute, 40 the invention has been described in language more or less specific as to certain structural features it is to be understood that the invention is not limited to any specific details, but that the means and construction herein 45 described comprise but one mode of putting the invention into effect, and the invention is therefore claimed broadly and in any of its possible forms or modifications within 50 the scope of the appended claims.

Having thus described my invention, I 55 claim,

1. A lamp comprising a housing, an illuminating element fixed in relation with the housing and a light control element movable 60 in a path concentric with the illuminating element to different radial positions in relation therewith to vary the direction of the rays of light from said illuminating element.

2. The combination with a dirigible 65 vehicle of a lamp immovably fixed in its rela-

tion therewith, a plurality of illuminating faces for said lamp arranged angularly one with the other, and means for directing the shaft of light from the lamp through any one of the faces and excluding the light from 70 the remaining face, such directing means being variable in unison with the deviations of the vehicle from a straight path.

3. The combination with a fixed lamp having a plurality of illuminating faces and 75 a stationary source of illumination common to all the faces, of a variable element capable of adjustment independent of the lamp for directing the shaft of light through one of the illuminating faces to the exclusion of 80 the remaining faces.

4. A lamp comprising a housing having a plurality of illuminating faces, a source of illumination therein, a variable control element movable into and out of registry with 85 the different illuminating faces to cause the light from said source of illumination to be transmitted through different illuminating faces.

5. The combination with a fixed lamp 90 having a plurality of illuminating faces, a fixed source of illumination common to all the faces, of a variable reflector adapted to be moved in a path concentric with the source of illumination into registry with 95 any one of the illuminating faces, whereby the shaft of light may be directed through any one of the several illuminating faces.

6. The combination with a fixed lamp having a plurality of illuminating faces of a 100 variable reflector adapted to be moved into registry with any one of the illuminating faces, whereby the shaft of light may be directed through any one of the several illuminating faces, and a blind moving in unison with the reflector adapted to close the remaining illuminating faces against the escape of light.

7. A lamp housing, an illuminating element within the housing, and a control element movable to different positions concentric with the illuminating element to cause the light from said element to be cast in different radial directions in relation with the said illuminating element. 110

8. The combination with a dirigible vehicle of a lamp housing fixed in its relation therewith, an illuminating element fixed in relation with the housing, and a control element movable in a path concentric with the illuminating element, adapted by its adjustment to direct the shaft of light in various radial directions from the fixed lamp, and means for adjusting the control element in unison with the deviations of the vehicle 120 from a straight path.

9. In a lamp a fixed housing, an illuminating member fixed in its relation with the housing, a pivotally mounted sleeve within the housing, within which the illuminating 130

member projects and a reflector mounted in one end of said sleeve, the other end of said sleeve being unobstructed to light, said sleeve being adjustable to different radial positions 5 independent of the housing and illuminating member.

10. The combination with a dirigible vehicle of a lamp comprising a housing fixed in its relation with the vehicle, a pivotally supported sleeve within the housing, a reflector carried by the sleeve, an illuminating element fixed in relation with the housing and projecting within the sleeve, and means for adjusting the sleeve to different radial 15 positions in unison with the deviation of the vehicle from a straight path.

11. The combination with a dirigible vehicle of a lamp comprising a housing fixed in its relation with the vehicle, and an illuminating element fixed in its relation with the housing, a variable control element movable in an arcuate path concentric with the illuminating element adapted to cast the direction of the shaft of light in different 20 radial directions independent of any radial adjustment of the lamp, and means for vary- 25

ing the control element in unison with the deviations of the vehicle from a straight path.

12. The combination with a dirigible vehicle of two sources of illumination fixed in their relation one with the other and with the vehicle, a control element for the light from each source of illumination normally directing their shafts of light in parallel 30 lines, said control elements being adjustable independent of the sources of illumination and independent of each other whereby the shafts of light may be directed in lines angular, one with the other without varying 35 the relation of the sources of illumination one with the other or with the vehicle, and means to independently adjust the control elements according to the direction of deviation of the vehicle from a straight path and 40 in unison with such deviation.

In testimony whereof, I have hereunto set my hand this 23rd day of April, 1913.

WILLIAM B. MEEKER.
